METHOD OF MAKING CHECKSTRAPS

Latt J. Carter, Kannapolis, N. C., assignor to
Graton & Knight Company, Worcester, Mass.,
a corporation of Massachusetts

Original application February 26, 1944, Serial No.
523,991. Divided and this application January
17, 1945, Serial No. 573,291

4 Claims. (Cl. 69—21)

1

My present invention is a divisional of my prior and copending application Ser. No. 523,991, filed February 26, 1944, now Patent No. 2,371,025, granted March 6, 1945, covering my improved check strap as an article of manufacture; the present divisional application being directed to cover and protect the method of manufacturing said check strap.

As explained in my said parent application, my present invention enables a check strap to be manufactured and utilized, wherein the open ends of the strap can be threaded thru the friction clutch or other parts of a loom without dismantling the loom, and may thereupon have the open ends united, preferably, thru an intermediate plug member, thus completing the assembly of the check strap directly on the loom and, preferably also, with means to provide a considerable range of adjustment for the length of strap desired during the operation of joining the ends and plug.

Furthermore, my present method and the check strap resulting therefrom provides a preformed and predetermined bevelled face on the plug and, preferably, a preformed molded bevelled surface on the middle portion of the check strap opposite the plug, so that the benefit and advantage of full contact with the picker stick during its oscillations within the confines of the check strap is secured. Thus, by premolding the middle portion of the check strap into a loop and assembling a plug member or a series of members for width and stick-contacting bevel or face desired, I secure the advantages of an even wear and longer life with my novel type of check strap, as well as increasing the checking operation by a wedging action at the plug end.

A further and most important feature of my present improved check strap consists in the universal adjustability accorded by my novel construction. Thus, by forming the open-end loop of a length and size sufficient for a larger, or the largest, looms intended to be supplied, and thereupon forming a set or series of plug layers, each with a plurality of spaced and adjusted openings or markings in each end portion to which the securing bolts are fitted, I am able to make from a single standard blank a large range of variably sized check straps, both in length and width at the plug-holding end.

These perforations in adjusted or spaced position, or markings for same, would be gauged to correspond with the standard lengths of looms within the range for which the check strap is made. Such adjustments could be either marked

2

1, 2, and 3 for size, and/or could be marked with the standard size of the loop check straps heretofore employed, such as 22, 23, 24, etc. By this arrangement, a single standard line of check straps can be kept in stock instead of a large number and series, which require separate book-keeping, storage, and handling; and when new check straps are desired the same can be promptly assembled by selecting the necessary number of layers for the width of plug and fitting the bolts thru the proper end portions of a strap for the size and length required.

I may also simply mark the end portions of the check strap where they are brought together to form the loop and make the perforations at the last moment just before completing and assembling the same, thus leaving the rest of the end unperforated; or, as above noted, I can make the series of perforations for the holding bolts, thereby having the strap ready to receive said bolts at any sized number which it is desired to supply. This feature is of great importance.

In carrying out my present method, I prepare a check strap of sufficient length to permit a pre-molding of the middle portion in forming the strap into a U-shaped contour, together with sufficient length for each side or arm of the U to permit adjustment for the greatest length of loom and picker-stick oscillations desired. The series of perforations have this adjustable length feature or a series of markings therefor can be made either before, during, or after this pre-molding operation; and where one or more markings for the uniting bolts are employed, the perforations can be made after the check strap is otherwise assembled in the friction clutches and on the loom.

I also prepare a series or set of plug members which may be either a single plug of suitable contour to cooperate and align with the bolt or rivet holes in the ends of the arms, said plug member preferably having a preformed beveled face to correspond with the pre-formed molded bevel at the base of the U in the check strap, viz. at the opposite end.

Thus the picker stick during the checking operation will strike only against the middle of the check strap at the premolded portion; and at the other end will strike on the plug at the pre-bevelled portion. Preferably, I make the plug end of a series of layers so that any width desired can be instantly assembled when putting the bolts or rivets thru the ends and the intermediate plug member or members.

Also, preferably, I utilize a double-layered

check strap construction as shown and claimed in the patent to Mark C. Howarth No. 2,291,587 of July 28, 1942, as such a double-layered construction is peculiarly beneficial to the loop and plug feature of my present open end check strap, giving strength and increased wear and, hence, long life to the completed strap.

Referring to the drawing illustrating preferred embodiments of carrying out my method:

Fig. 1 is a side view, partly broken away, showing my loop check strap;

Fig. 2 is a plan view showing the check strap threaded thru the friction devices on a loom, the latter being partly in cross section;

Fig. 3 is a plan view of a modified form; and

Fig. 4 is a cross-sectional view on the line 4—4 of Fig. 3;

Fig. 5 is a fragmentary view showing the range of adjustment afforded by my improved check strap.

As shown in the drawing, my improved check strap is of suitable length and of any material desired, preferably being a double-fold leather strap, as above noted, and is herein shown for illustrative purposes, the strap being designated generally as 1, with the middle portion in the form of a bow or U-shape 2, preferably molded into this shape and with the opposite ends 4 and 5 being united together by bolts 8 and 9 with the intermediate plug member 10. These bolts are detachably secured with nuts 11—11 as shown, or in any other suitable manner, the intermediate plug member 10 being provided with a bevelled face 12 on the inner or loop end, which bevel is substantially that of the picker stick 20 at the end of the oscillation to give a substantially full-length contact on the plug member.

This plug member 10 may be of any suitable material and of any thickness desired, being herein shown as comprising two or more leather layers. Where a double or folded check strap, such as that of said Howarth patent is employed, I form the same with the opposite edges 14 and 15 arranged at the top of the check strap, and the folded edge 16 at the bottom to obtain the advantages explained in said Howarth patent. With the loop check strap construction as thus explained, the nuts 11 or other fastening means can be readily released and the end portions of the check strap 4 and 5 threaded thru the friction members, usually employed on a loom where a circular strap is desired.

As herein shown in diagrammatic form, these friction members comprise adjustable rounded members 18 and 19 on each side thru which the check strap is threaded and, thus, the strap encircles the picker stick 20. These friction members 18 and 19 can be released for threading thru the ends 4 and 5 and arms of my check strap and, therefore, the friction devices can be adjusted, as desired, and the bolts 8 and 9 uniting the ends and the intermediate plug are assembled.

The width of the plug 10 can be variable. As shown in Fig. 2, the width of the plug 10 is less than the width of the picker stick 20 and, therefore, as the picker stick approaches the plug end of my check strap, it will engage the sides of the check strap and afford a wedging and checking action before the stick actually strikes the face 12 of the plug. Such wedging is released by the check strap sliding bodily thru the friction members 18 and 19 so there will be no interference with the stick at the start of the return stroke.

In Fig. 3 I have illustrated a plug 25 of a width substantially equal to that of the picker stick 20 with which the check strap is to operate, so that the picker stick will strike the bevelled face 26 of this wider plug 25 without the wedging action on the side walls of the check strap.

In the form shown in Figs. 3 and 4, I may also mold the middle portion of the check strap constituting the bow or U-shaped portion 30 opposite the plug end with a pre-bevelled contour 31, as shown in Fig. 4.

It will thus be appreciated that I have devised a check strap construction suitable for application to a loom where heretofore a circular or continuous check strap has been employed, and which latter required the partial removal of the loom-friction devices to apply the same; and I have also developed a new and novel check strap construction which is extremely simple, efficient, and wear-resistant. In case of wear on the plug members 12 or 25, they can be readily renewed and plug members of different width and different material can be utilized, if found desirable. I prefer to form these plug members of layers of leather of substantially the same strength and density as that of the strap 1, and can thus readily build up the thickness of the plug to vary the wedging action of the picker stick where a narrower plug is employed or into full width of the picker stick, as shown in Figs. 3 and 4.

As shown in Fig. 5, I have illustrated different methods of fitting or marking the end portions of the check strap 1 so as to provide for universal adjustability to looms of varying sizes within a substantial range. As above noted, this is a very important feature, as heretofore check straps, particularly those made in circular form, had to be originally built of predetermined length to fit the loom to which it is intended the same was to be applied, these being designated by different numbers and sizes.

Therefore, a manufacturer had to have on hand a substantial supply of different sized check straps, requiring separate handling, bookkeeping, accounting, etc., and thus, one check strap made for one size loom could not be substituted for a different size loom.

By means of my present open-end loop construction, I am enabled to have one standard size provided with suitable adjusting designations so that from a single stock supply on hand, check straps can be readily and instantly assembled to fit any size loom desired within the range accorded by the length of the strap.

For this purpose, as shown in Fig. 5, I may provide a set of bolt-receiving holes properly spaced for the different sized straps, within the range accorded by the length of the check strap, which series of holes are designated at 30—30, which holes are appropriately spaced to receive the bolt holes 8 and 9 when assembling the loop strap. Two series of such bolt openings 30 can be arranged at the top and bottom of each end portion of the strap 1 and in spaced relation cooperating with the corresponding bolt openings in the plug 10, as will be appreciated.

These adjustments can be suitably marked to designate the size and, as such sizes are usually defined in length, I have illustrated the same as marked "22," "23," and "24," so that the bolts fitted thru the corresponding "22" openings would be for the shorter loops desired, and those for the longer openings nearer the end portions would make the check strap a correspondingly longer length.

Instead of performing the holes 30, I may simply designate the properly spaced points in which a single hole can be quickly punched when the strap is to be assembled with the plug.

I claim:

1. The improved process of making an open end check strap of the kind described, with an intermediate plug united at the open ends of said strap, which consists in preparing a check strap of suitable length to permit a pre-beveling and premolding at the middle portion, together with a range of adjustability for length at the open end portion, thereupon premolding the middle portion into U-shaped contour with a predetermined bevel, preparing a plug member for fitting between the open ends, said plug member having a preformed face substantially corresponding to the preformed bevel of the U-portion, and thereupon uniting the open ends and the intermediate plug to complete the check strap.

2. The improved process of making a check strap with an intermediate plug member uniting the open ends of a U-formed strap of the kind described, which consists in molding the central portion of the check strap into the contour of a U-shaped loop, forming perforations in the opposite arms of the U in alignment, preparing a plug for assembly between said arms, said plug having preformed holes to cooperate with those in the open ends, said plug having a preformed face construction and arranged for assembly with the open ends, and bevelled from the bottom portion upwardly to give full face contact to a picker stick oscillating within the loop of the check strap thus formed, thereupon uniting the end portions of the arms and intermediate plug by positioning the same with selected holes thru arms and plug in alignment and fitting

therein rivets, bolts, or the like to complete the check strap.

3. The improved method of making a check strap having a U-shaped contour and an intermediate plug member at the open ends of the strap, which consists in preparing a leather blank of twice the width of the strap intended to be made and of a sufficient length to allow for adjustability of the longest length of loom with which the strap is to be used, thereupon folding said strap lengthwise to constitute a wear-resisting layer and a reinforcing layer, premolding the middle portion of said folded strap to a predetermined contour, with a bevel extending from the integral bottom portion uniting said two layers upwardly toward the folded edge portion, and thereupon applying an intermediate plug between the open ends of the arms uniting said plug and arms, said plug having a bevelled face cooperating with that on the molded middle portion.

4. The improved process of making a check strap with an intermediate plug member uniting the open ends of a U-formed strap of the kind described, which consists in molding the central portion of the check strap into the contour of a U-shaped loop, forming perforations in the opposite arms of the U in alignment, preparing a plug comprising a plurality of layers for assembling between said arms, said layers having preformed holes therethru to cooperate with those in the open ends, each layer having a preformed face and a selective number of said layers being assembled and united with the open ends of the check strap by fastening elements thru said preformed holes in alignment thru both arms and the plug.

LATT J. CARTER.
